UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 13,378, dated October 31, 1882.

Application filed August 11, 1882. Term of patent 3½ years.

To all whom it may concern:

Be it known that I, WINTHROP L. JACOBS, of East Orange, in the State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

Disposed at regular intervals over a plain ground are large and variously-shaped geometrical and right-lined figures with irregular

angular outlines, projections, and divisions. Between these larger figures the ground is well filled in with small circular and right-lined figures, and arbitrary forms of various and irregular shapes and irregularly connected, 15 as is fully shown in the accompanying photograph.

I claim—

The design for carpets, substantially as shown and described.

WINTHROP L. JACOBS.
